UNITED STATES PATENT OFFICE.

REINHART W. PITTMAN, OF NEW YORK, N. Y.

FIRE EXTINGUISHER.

Application filed July 21, 1920. Serial No. 397,924.

To all whom it may concern:

Be it known that I, REINHART W. PITTMAN, a citizen of the United States, and a resident of the borough of Manhattan, in the city, county, and State of New York, have invented certain new and useful Improvements in Fire Extinguishers, of which the following is a specification.

This invention relates to sprayers adapted for fire extinguishers of the type in which the fire extinguishing medium is discharged from a container or reservoir therefor by pump mechanism, and it is the primary object of the invention to provide an improved apparatus of this class to increase the efficiency thereof over the commercial fire extinguishers of this type to discharge the contents of the reservoir in a continuous and uninterrupted stream with the least amount of exertion on the part of the user.

The invention relates to a type of extinguisher in which the pumping mechanism is operated to discharge the contents from the reservoir by a reciprocable actuating member and to discharge the contents upon each movement of said member. In the operation of fire extinguishers of this type the reservoir is held in one hand and the actuating member is manipulated by grasping a hand grip connected thereto by the other hand and direct the discharged stream by the hand grasping the reservoir. The length of the reservoir of commercial extinguishers of this type so far as known is approximately twelve inches and the operating stroke of the actuating member is substantially the length of the reservoir with the result that as the actuating member approaches the limit of its outermost movement there is a considerable spread between the hands of the user and great difficulty is experienced in directing the discharged stream. Furthermore, due to the volume of the fire extinguishing medium in the pump in front of the operating face of the piston during the initial portion of the stroke necessitates the exertion of considerable power in the operation of the actuating member. It is an object of the invention to overcome the above disadvantages by providing a device in which the actuating member has a relatively short movement to perform the function of discharging the contents of the reservoir.

It is a further object of the invention to

provide a fire extinguisher of this type in which the pumping mechanism to discharge the contents from the reservoir comprises a plurality of pumps having connection with the reservoir and a common discharge outlet from the reservoir.

It is another object of the invention to provide a fire extinguisher of this character comprising a plurality of pumps having a discharge outlet common to all of the pumps in which an intake is provided which is common to all of the pumps having an inlet from opposite ends and the side of the reservoir constructed and arranged to shut off the inlet to the pumping mechanism at the end which is uppermost and open the inlet to the pumping mechanism at the end which is lowermost, and the inlets adapted to assume a position by gravity at the side of the reservoir which is lowermost.

It is a still further object of the invention to provide a fire extinguisher of this type in which the pumping mechanism comprises a pair of cylinder pumps including reciprocable pistons in which an actuator is provided which is common to both of the pumps and constructed and arranged to reciprocate both of the pistons simultaneously with the direction of movement of one piston opposite to the direction of movement of the other piston, and the pumps arranged with valve mechanism to alternately connect the pumps to the reservoir and discharge outlet of the reservoir.

It is still another object of the invention to provide in an extinguisher of this type improved valve mechanism to control the discharge outlet of the reservoir, and operable by the actuating member to be moved to and maintained in position to close the discharge outlet of the reservoir.

Other objects and advantages will hereinafter appear.

In the drawings accompanying and forming a part of this specification Figure 1 is a longitudinal sectional view of a spraying device embodying my invention, and illustrating the arrangement of the pumping mechanism, the connection thereof with the outlet of the reservoir, the actuating means for the pumping mechanism and the means to close the outlet of the reservoir.

Figure 2 is a longitudinal sectional view showing the construction and arrangement of intake or pick up means to the pumping

mechanism to connect the latter with the reservoir at the side and end which is lowermost.

Figure 3 is a cross sectional view taken on the line 3—3 of Figure 1 looking in the direction of the arrow and showing the connection of the intake means with the pumping mechanism.

Figure 4 is a front elevation of a plate to co-operate with the member shown in Figure 3.

Figure 5 is a cross sectional view taken on the line 5—5 of Figure 1 looking in the direction of the arrows.

Figure 6 is a detail view in perspective to show the manner of mounting one end of the pumping mechanism, the connection of the pumping mechanism with the outlet of the reservoir and the intake means, and the connection of the latter at one end of the reservoir.

Figure 7 is a longitudinal sectional view showing a modification of the intake means from the reservoir to the pumping mechanism.

Figure 8 is an enlarged sectional end elevation taken on the line 8—8 of Figure 7.

Figure 9 is a front elevation of a head for supporting the pumping mechanism in the reservoir shown at the left of Figure 7.

Figure 10 is an end elevation of one of the intake members shown in Figure 7.

Figure 11 is a longitudinal sectional view taken substantially through the center of Figure 10.

Figure 12 is a perspective view of the parts disassembled to support one end of the pumping mechanism by the nozzle.

Figure 13 is a sectional side elevation to show the connection of a piston with a piston rod; and

Figure 14 is a perspective view, partly in section, to show the manner of mounting one end of the pumping mechanism in Figure 7 upon the stuffing box for the actuator rod.

In carrying out the invention a conventional form of container or reservoir is provided having a body portion 14 preferably of cylindrical shape in cross section having a closure 15 at one end with a discharge nozzle 16 axially thereof, said closure being fixed to the end of the body portion in a suitable manner and dished or depressed as shown, the opposite end has a closure 17 secured thereto.

To discharge the contents of the reservoir, preferably consisting of a liquid and constituting a fire extinguishing liquid when the device is used as a fire extinguisher, is discharged by means of a pumping mechanism connected to the reservoir and discharge nozzle 16, said pumping mechanism comprising a plurality of pumps and

shown as of the cylinder type. In the embodiment shown in the drawings a pair of pumps are utilized located at opposite sides of and extending parallel with the longitudinal axis of the reservoir, and comprising a pair of cylinders 18, 19 mounted and fixed at one end upon projections or bosses 20 projecting from one side of a head 21 having a channel 22 in the opposite face, Figure 3. The channel 22 has a port 23 and ports 24 in the bosses 20 upon which the cylinders are mounted communicating with the cylinders to constitute outlets for said passage and inlets to the respective cylinders. Ports 25 through the bosses 20 communicate with and constitute outlets for the cylinders connected in communication with the outlet in the nozzle 16 concentric of the reservoir end by passages or channels 27 in a manner hereinafter set forth. For facilitating manufacture the channels 22 and 27 are formed in one face of the head 21, and to provide closed passages a plate or member 28 (Figure 4) is secured to said face of the head 21. To secure the plate and head against a shouldered tubular member 21' having a bore 26 passes axially through the head and plate with the ends projecting therefrom and the shoulder thereof engaging the head, and a nut 29 threaded to the projecting end of said member at the outer face of the plate 28, said member 21' also having a transverse port in line with the channel 27 in the head and constituting a part thereof. The plate 28 has a port 30 extending through a lateral projection 31 and which port is adapted to align with a port 32 in a boss 35' projecting from the face of the head opposite to the plate 28, for a purpose to be hereinafter described. The ports 24 leading into the cylinders are controlled by spring influenced suction valves 33 and the ports 25 are controlled by spring influenced valves 34, both of which are shown as of the ball type.

A casing in the form of a tube 35 is mounted at one end upon the boss 35' in communication with the head port 32 and the port 30 in the plate 28. The opposite end of the casing has a tube 36 connected thereto having a restricted bore relative to the bore of the casing, said tube being connected at the end opposite to the casing with a port 37 in a member or head 38, said port 37 extending through a projection 39 extending laterally from said head 38. The casing 35 is connected to the inlet port 23 of the channel 22 in the head 21 and thereby with the ports 24 leading into the cylinders by a tube or pipe 40 connected at one end to said port 23 and the opposite end connected to a port 41 in the casing 35.

By this arrangement the pump cylinders

are connected in a rigid structure with the heads 38 and 21 and by means of which heads the pump cylinders with the connected casing are adapted to be mounted in the reservoir to have rotative movement on an axis in line with the axis of the reservoir with the ported projections 31 and 39 of the heads in alignment and extending to opposite ends and near the side of the reservoir, 5 preferably with the extremities lying contiguous to the juncture of the closures 15, 17 with the body of the reservoir, and thereby connecting the pump cylinders with the reservoir at the side and opposite ends of the reservoir. To mount the pump cylinders with the connected casing 35 to rotate on an axis in line of the axis of the reservoir the nozzle 16 has a tubular stem to extend into the reservoir and loosely engaging in 10 the bore of the projecting member 21, with the opening in the nozzle stem in communication with the bore 26, in the member 21 and nozzle, the nozzle being fixed to the closure 15 in a suitable manner, as by soldering. 15 The head 38 is loosely mounted on a sleeve 42 constituting part of a stuffing box mounted in the closure 17.

The cylinders 18, 19 are arranged diametrically opposite each other in line with the axis of the reservoir, and the casing 35 is located substantially midway between the cylinders and extends parallel with the cylinder and will automatically assume a position by gravity below the axis of the reservoir and position the inlets 39 near the side portion of the reservoir which is lowermost in all positions of the reservoir. The heads 21, 38 may be weighted adjacent the inlets 31, 39 and supported eccentric to the axis of said heads thereby facilitating the positioning of the intake near the side portion of the reservoir which is lowermost.

To connect the cylinders with the reservoir at the end which is lowermost the casing 35 is arranged as a valve chamber by fitting disks 44, 45 in spaced relation in the casing; the disks being axially perforated and arranged with valve seats at the outer sides, the opening and closing of which perforations is controlled by gravity valve mechanism comprising a pair of valves 46, 47 connected by a rod 48 of greater length than the space between the disks whereby said valves are adapted to operate inversely in unison. 45 Should the nozzle end of the reservoir be tilted downward from the horizontal the valve 46 will be seated against the valve seat 44 shutting off the cylinders from the upper portion of the reservoir through the inlet port 37 in member 39 and open the cylinders to the end of the reservoir which is lowermost through the port 30 of member 31, casing 35, valve disk 45 and tube 40 connected to the casing or valve chamber at a point between the valve disks 44, 45. It will be ob-

vious that should the end of the reservoir opposite to the discharge nozzle be tilted downward from the horizontal that the valve 45 will be seated and shut off the cylinders from the reservoir through inlet port 30 in member 31 and seat the valve 47 opening the cylinders 18, 19 to the reservoir through the intake port 37. It will furthermore be obvious that by the arrangement described the cylinders 18, 19 are provided with an inlet valve mechanism from the reservoir which is common to all of the cylinders and adapted to automatically and by gravity position an inlet to said cylinders in the lower portion of the reservoir with said inlet open to the reservoir in all positions thereof.

To control the entrance of the contents of the reservoir to the cylinders 18, 19 and discharge the same from the reservoir pistons 49, 50 having suitable packing are reciprocably mounted in the cylinders, each piston having a piston rod 51, 52 connected thereto and extending through the open end of the cylinders opposite the valve controlled inlet and outlet ports and arranged with rack teeth, as shown at 53, 54 meshing with a pinion 55 rotatably carried by a bracket 56 connected to and maintaining the cylinders 18, 19 at the ends opposite to the head 21 in spaced relation, said bracket also having lateral projections 57, 58 arranged to form guides for the piston rods and maintain the teeth thereof in mesh with the pinion 55. The cylinders 18, 19 are of less length than the reservoir and the piston rods are adapted to have reciprocatory movement within the reservoir.

The piston rods and pistons are reciprocated by an actuator common to both and comprising a rod 59 slidably mounted in the stuffing box 43 having a rotatable connection with a member 60 connected to one of the piston rods, in the present instance the rod 51, and having a handle 61 connected to the outer end to manipulate the rod. The pistons are so arranged that when one of the pistons is in its innermost position in a cylinder the other cylinder is in its outermost position, and by reciprocating the actuator rod the pistons will be simultaneously reciprocated, but in a direction inversely to each other. By this arrangement the pumps are operated in alternation in discharging the contents from the reservoir. By the rotatable connection of the actuator rod 59 with the pumping mechanism the piston mechanism is adapted to rotate freely with the cylinders 18, 19.

To prevent leakage of the contents of the reservoir through the discharge nozzle and shut off the interior of the reservoir from the atmosphere through the discharge nozzle valve mechanism is provided to close the orifice through said nozzle, and comprise a

valve 62 carried by a stem 63 to co-operate with a seat at the inner end of the stem of the nozzle, the valve stem being slidably mounted in the member 21' in the head 21 and a guide 64 and yieldingly urged in a direction to unseat the valve by a spring 65, said movement being limited by an adjustable collar 66 on the valve stem abutting against the guide 64. The free end of the valve stem is arranged to lie in the path of movement of a flange 67 on the connection of the actuator rod with a piston rod and be engaged by said flange and moved against the action of the spring 65 to seat the valve as the actuator rod approaches its innermost position.

To lock the actuator rod 59 in position to maintain the outlet closing valve seated means are provided to lock said actuator rod against reciprocation and in its innermost position. For this purpose the connection of the operating handle 61 to the rod is arranged to permit of rotative movement of the handle on the rod and the handle and rod to have a limited longitudinal movement relative to each other by providing a portion of the rod engaging in the handle with a reduced portion 68 engaged by a pin 69 extending transversely through the shank of the handle. The handle and rod are urged in opposite directions to the limit of their movement with the pin 69 engaging a shoulder formed by the reduced portion 68 of the rod by a spring 70 confined between the end of the rod and a screw plug 71 threaded into the outer end of the opening for the actuator rod. As the actuator rod approaches its innermost position the flange 67 will abut against the end of the valve stem and move said stem to seat the valve 62, the tension of the spring 70 being such as to overcome the tension of the valve spring 65. As the valve is seated the handle is rotatably adjusted to register diametrically opposite recesses in an annular flange 72 at the end of the shank of the handle with opposite cam portions 73 projecting laterally from the stuffing box when the handle is moved longitudinally of the actuator rod against the tension of the spring 70 until the cam portions 73 are positioned in the recesses of the flange 72 when the handle is given a partial rotation causing said cam projections 73 to engage in back of the flange portion 72 and lock the actuator rod against movement and the valve 62 against its seat. To unseat the valve 62 it is only necessary to give the handle 61 a partial rotation and draw the same outward thereby moving the flange of the support of the actuator rod out of engagement with the end of the valve stem 63 when the valve will be unseated by the spring 65.

It will be obvious that by the arrangement described that the contents of the reservoir is discharged by a plurality of pumps, said pumps having inlet means from the reservoir which, as well as the outlet of the reservoir, is common to all of the pumps, and that the actuator is common to all of the pumps. Furthermore, that while the reciprocable movements of the pump pistons are comparatively short relative to the length of the reservoir a continuous and uninterrupted stream is discharged from the nozzle during the actuation of the pumping mechanism, and it is just as effective, if not more so, as in devices of this character in which the pump piston has a movement substantially the full length of the reservoir, and requiring the least amount of energy in the operation of the same.

The construction of the pumping mechanism and the connection thereof with the discharge nozzle shown in Figure 7 is the same as that shown in Figures 1 to 6. However, instead of the pumping mechanism with the connected intake means being rotatably supported in the reservoir the pumping mechanism is supported in fixed position. For this purpose the nozzle instead of being fixed to the closure 15 with the stem thereof loosely engaging in the projecting end of the member 21' the nozzle stem is threaded into said projection, as shown at 75, thereby clamping said end of the pumping mechanism to the closure 15. The head 38 for supporting the opposite end of the pumping mechanism is arranged with a longitudinally split hub having a clamping screw 76 to releasably secure the head to the sleeve or bushing 42. The inlets to the pumps are connected to the ports 32, 37 in the heads 21, 38 through the gravity valve carrying casing 35 the same as in Figures 1 and 2 to connect the pump mechanism with opposite ends of the reservoir. To connect the pumping mechanism with the reservoir near the side which is lowermost in all positions of the reservoir intake members 77, 78 are provided arranged to be at all times in communication with the inlet ports 32, 37 of the heads 21, 38 and adapted to assume a position by gravity below the axis of the reservoir in all positions thereof. These inlet members comprise segments rotatably supported upon the sleeve 42 and the member 21' and extend radially to the side of the reservoir with ports 81, 82 extending through the peripheral portion of said members and communicating with annular recesses 83, 84 in the faces of the respective members lying contiguous to the head 38 and the plate 28, and with said head and plate constituting chambers with which the ports 32, 37 are in communication in all positions of said members 77, 78. Suitable

packing, such as felt washers 85, is interposed between the intake members 77, 78 and the head 38 and plate 28.

Having thus described my invention I claim:

1. The combination with a reservoir, of a plurality of pumps mounted in the reservoir having a suction inlet from opposite ends of the reservoir common to all of the pumps, an outlet from one end of the reservoir common to all of the pumps, and means projecting from the end of the reservoir opposite the outlet to actuate the pumps in alternation to discharge the contents of the reservoir. 65
2. The combination with a reservoir, of a plurality of pumps having suction inlets, an intake common to all of the suction inlets of the pumps having an inlet from opposite ends of the reservoir operated by gravity to automatically position inlets thereto below the axis of the reservoir, an outlet from the reservoir common to all of the pumps, and means to actuate the pumps in alternation to discharge the contents of the reservoir. 70
3. The combination with a liquid carrying reservoir, of a plurality of pumps having inlet ports and outlet ports in communication with the discharge outlet common to all of the outlet ports; means common to all of the pumps operative to actuate the pumps in alternation; valve mechanism operable to control the entrance of liquid to and its discharge from the pumps; intake means in the reservoir in communication with the inlets to the pumps and arranged to be positioned by gravity to connect the pumps with the liquid in that portion of the reservoir which is lowermost; and a valve for the discharge outlet arranged to be maintained in closed position by the pump actuating means in one position thereof. 75
4. The combination with a reservoir having an outlet, of a plurality of cylinders in the reservoir having inlet ports and outlet ports connected to the reservoir outlet; pistons to reciprocate in the cylinders; valve mechanism operable to control the inlet and outlet ports of the cylinders during the reciprocation of the pistons; an intake common to all of the inlet ports of the cylinders having an inlet from opposite ends of the reservoir; and operating means common to all of the pistons to actuate the pistons in alternation to discharge the contents of the reservoir. 80
5. The combination with a reservoir having an outlet, of a plurality of cylinders in the reservoir; pistons to reciprocate in the cylinders; suction inlets to the cylinders; valve controlled outlets from the cylinders connected to the reservoir outlet; an intake common to the suction inlets of all the cylinders, said intake having an inlet from opposite ends of the reservoir and operable by gravity to position the inlets below the axis of the reservoir; and an operating rod common to all of the pistons operable to actuate the pistons to draw the contents from the reservoir to and discharge the same from the cylinders in alternation. 85
6. The combination with a reservoir having an outlet, of a plurality of pumps in the reservoir connected to the reservoir and the reservoir outlet; means operable to actuate the pumps in alternation; and a valve for the reservoir outlet in the connection of the outlets of the pumps and reservoir and arranged to be maintained in closed position by the pump actuating means in one position thereof. 90
7. The combination with a reservoir having an outlet, of a plurality of cylinder pumps in the reservoir connected to the reservoir and the reservoir outlet, a reciprocable rod to actuate the pumps in alternation; and a valve for the reservoir outlet normally urged to open position and arranged to be maintained in closed position by the pump actuating rod in one position thereof. 95
8. The combination with a reservoir having an outlet, of a plurality of cylinder pumps in the reservoir connected to the reservoir and reservoir outlet; an operating rod operable to actuate the pumps in alternation; a valve for the reservoir outlet; means to yieldingly urge the valve to open position; said valve arranged to be maintained in outlet closing position by the pump operating rod in one position thereof; and means to lock the operating rod in position with the valve in outlet closing position. 100
9. The combination with a reservoir having an outlet, of a plurality of cylinder pumps in the reservoir connected to the reservoir and reservoir outlet; an operating rod arranged to operate the pumps in alternation; a valve to control the reservoir outlet having a stem whereby it is slidably supported, a spring to co-operate with the valve stem to urge the stem and valve in a direction to open the outlet, and said valve stem adapted to be engaged by the pump actuating rod to move the stem to position the valve to close the outlet; and means to lock the pump actuating rod in position with the valve in outlet closing position. 110
10. The combination with a reservoir having an outlet, of a plurality of pumps having suction inlets and valve controlled outlets connected to the reservoir outlet; means to actuate the pumps in alternation; a gravity valve controlled intake from the reservoir common to the suction inlets of all of the 115
- 120
- 125

pumps adapted to automatically position an inlet thereto in the lower portion of the reservoir in all positions of the reservoir and provide a continuous passage from said 5 inlet to the suction inlets of the pumps and valve means operative by the pump actuating means in one position thereof to shut off the liquid in the reservoir from the outlet.

11. The combination with a reservoir, of 10 a plurality of pumps having suction inlets; an outlet from the reservoir common to all of the pumps; an actuator common to all of the pumps; an intake having a pair of inlets common to all of the suction inlets of 15 the pumps adapted to position an inlet thereto by gravity in the lower portion of the reservoir in all positions of the reservoir and a pair of valves for said intake arranged to operate in unison adapted to shut 20 off the inlet to the intake which is uppermost and open the inlet which is lowermost to provide a continuous passage from said inlet to the suction inlets of the pumps.

12. The combination with a reservoir, of 25 a plurality of pumps having suction inlets; an outlet from the reservoir common to all of the pumps; an actuator for the pumps; and inlet valve mechanism common to all of the pumps having an inlet from opposite 30 ends of the reservoir adapted to position the inlets by gravity near the side of the reservoir which is lowermost in all positions of the reservoir and provide a continuous passage from either of said inlets to the suction 35 inlets of the pumps; and a valve interposed between the pumps and discharge outlet operable by the pump actuator in one position thereof to maintain the same closed to shut 40 off the liquid in the reservoir from the discharge outlet.

13. The combination with a reservoir, of 45 a plurality of pumps having suction inlets; an outlet from the reservoir common to all of the pumps; an actuator for the pumps; a chamber common to all of the suction inlets of the pumps having an inlet from opposite ends of the reservoir and an outlet intermediate the inlets in communication with the reservoir outlet and adapted to 50 swing about the axis of the reservoir; and gravity valves in said chamber operable to shut off the inlet to said chamber which is uppermost and open the inlet to the chamber which is lowermost in all positions of the reservoir for the purpose specified.

14. The combination with a reservoir, of 55 a plurality of pumps having suction inlets; an outlet from the reservoir common to all of the pumps; an actuator for the pumps; a chamber common to all of the suction inlets of the pumps having an inlet from opposite ends of the reservoir and adapted to assume a position by gravity near the side of the reservoir which is lowermost in all positions 60 of the reservoir; valves connected to one an-

other to operate inversely in unison to shut off the inlet to the chamber which is uppermost and open the inlet to the chamber which is lowermost for the purpose specified; valve mechanism for the reservoir outlet operable 70 by the pump actuator in one position thereof to close said outlet; and means to lock the pump actuator in said position with the valve for the discharge outlet in closed position.

15. The combination with a reservoir, of a plurality of pumps in the reservoir having suction inlets from the reservoir; a chamber having valve controlled ports from the pumps and an outlet to the exterior of the reservoir; means to actuate the pumps; and a valve operable by the pump actuator in one position thereof to shut off the outlet of the chamber.

16. The combination with a reservoir, of a plurality of pumps including cylinders in the reservoir having suction inlets from the reservoir; pistons to reciprocate in the pump cylinders; a chamber having valve controlled ports from the cylinders and an outlet to the exterior of the reservoir; means to reciprocate the pistons and actuate the pumps in alternation; a valve in said chamber to control the outlet from said chamber and normally urged to position to open said outlet, and adapted to be moved to position to close said outlet by the pump actuating means in one position thereof; and means to lock the pump actuating means against movement and the valve in position to shut off the outlet of the chamber.

17. The combination with a reservoir, of a plurality of cylinder pumps arranged to extend parallel with the axis of the reservoir having outlet means common to all of the pumps to the exterior of the reservoir and suction inlets from opposite ends of the reservoir common to all of the pumps, said pumps being adapted to rotate in unison about the axis of the reservoir; gravity valves to shut off the inlet from the reservoir which is uppermost; and an actuator for said pumps.

18. The combination with a reservoir, of a plurality of cylinder pumps arranged to extend parallel with the axis of the reservoir having outlet means common to all of the pumps to the exterior of the reservoir and suction inlets; means to actuate the pumps; intake means to the suction inlets having an inlet from opposite ends of the reservoir rotatable about the axis of the reservoir and adapted to assume a position by gravity near the side of the reservoir which is lowermost; and gravity valve mechanism operable to shut off the inlet to the intake means which is lowermost.

19. The combination with a reservoir having an outlet in one end in line with the axis of the reservoir, of a plurality of pump

cylinders in the reservoir each pump having an outlet connected to the reservoir outlet and suction inlets connected to the reservoir; pistons to reciprocate in said cylinders; an actuating rod slidably mounted in the end of the reservoir in line with the axis thereof opposite to the outlet; and means to connect said rod to the pistons to reciprocate said pistons simultaneously and in opposite directions for the purpose specified.

20. The combination with a reservoir having an outlet axially in one end, of a pair of cylinders in the reservoir having valve controlled outlets connected to the reservoir outlet and suction inlets connected to the reservoir; pistons to reciprocate in said cylinders; an actuating rod slidably mounted in the end of the reservoir in line with the axis thereof and opposite to the outlet and having connection with one of the pistons; and means to connect the other piston to and actuate the same from the first piston and in inverse direction thereto.

25. The combination with a reservoir having an outlet axially at one end, of a pair of pump cylinders in the reservoir having valve controlled outlets connected to the reservoir outlet and suction inlets connected to the reservoir; pistons to reciprocate in said cylinders; piston rods connected to said pistons; an actuating rod slidably mounted in the end of the reservoir in line with the axis thereof and opposite to the outlet and connected to one of the piston rods, and an operating connection between the piston rods arranged to reciprocate the pistons simultaneously in opposite direc-

tions by the reciprocation of the actuating rod for the purpose specified.

22. The combination with a reservoir having an outlet axially at one end, of a pair of pump cylinders in the reservoir having valve controlled outlets connected to the reservoir outlet and suction inlets connected to the reservoir; pistons to reciprocate in said cylinders; piston rods connected to said pistons arranged with rack teeth; a pinion to mesh with said rack teeth of the piston rods; and an actuating rod slidably mounted in the end of the reservoir in line with the axis thereof and opposite to the outlet and connected to one of the piston rods for the purpose specified.

23. The combination with a reservoir having an outlet, of a plurality of pumps in the reservoir having suction inlets and connected to the reservoir outlet; an actuator common to all of the pumps arranged to actuate the pumps in alternation; and inlet valve mechanism from the reservoir common to all of the pumps having an inlet from opposite ends of the reservoir and providing an unobstructed passage from said inlets to the suction inlets of the pumps, and adapted to automatically position said inlets at the side of the reservoir which is lowermost open and shut off the inlet which is uppermost from the reservoir and suction inlets of the pumps.

Signed at the city of New York, in the county of New York and State of New York, this 15th day of July, 1920.

REINHART W. PITTMAN.
